UNITED STATES PATENT OFFICE.

PATRICK J. CASSERLY, OF ELYRIA, OHIO.

SLIDING-DOOR FASTENER.

SPECIFICATION forming part of Letters Patent No. 777,332, dated December 13, 1904.

Application filed June 11, 1903. Serial No. 161,109. (No model.)

To all whom it may concern:

Be it known that I, PATRICK J. CASSERLY, a citizen of the United States of America, residing at Elyria, in the county of Lorain and State of Ohio, have invented certain new and useful Improvements in Fasteners for Sliding Doors, and I hereby declare the following to be a full, clear, and exact description of the invention, such as will enable others skilled in the art to 10 which it pertains to make and use the same.

This invention relates to improvements in fasteners for the sliding doors of freight-cars and warehouses.

The object of this invention is to provide a 15 fastener of the character indicated which is simple and durable in construction and not liable to get out of order.

With this object in view my invention consists in certain features of construction and 20 combinations of parts hereinafter described, and pointed out in the claims.

In the accompanying drawings, Figure 1 is a side elevation of a portion of a sliding door and door-casing and illustrates a fastener embodying my invention. Portions are broken away in this figure to reduce the size of the drawing. Fig. 2 is a vertical section on line 22, Fig. 1, looking in the direction indicated by the arrow. Fig. 3 is a top plan in horizontal section on line 33, Fig. 1. Fig. 4 is a side elevation, largely in section, illustrative of the operation of my improved fastener in actuating the door from an open into its closed position. Fig. 5 is a section taken vertically 35 through an end of the latch-plate of the fastener.

Referring to the said drawings, A designates a sliding door which engages at the top and bottom with parallel horizontally-arranged 40 slideways b, formed in the casing B, and C represents a jamb of the door-casing. In Figs. 1, 2, and 3 the door A is shown in its closed position.

The door A is provided at one side and at the 45 outer side in the case illustrated with a latch-plate D, which is removably secured to the said side of the said door by screws e. The plate D is provided at its outer side with a latch G, which is capable of being swung in a vertical plane, 50 being pivoted, as at H, horizontally to and

transversely of the plate D centrally between two seat-forming lugs d, with which the outer side of the said plate is provided and which project laterally and outwardly from the said plate. The lugs d are arranged in the same 55 or approximately same plane horizontally.

A detent-bearing plate K is removably secured by means of screws f to the jamb C externally of and next adjacent to the doorway at the outer side of the doorway. The latch G in its operative position, as shown in solid lines, Figs. 1 and 3, when the door A is in its closed position extends across the outer side of the plate K. The latch G is provided at its free end with two projections 6 and 7, arranged at the top and bottom, respectively, of the latch. The lower projection 7 depends from the latch and in the operative position of the latch and as shown in Figs. 1 and 3 overlaps the outer side of a vertically-arranged 70 detent-forming lug k, with which the plate K is provided. The lug k is therefore a stationary detent arranged to retain the latch in its operative position in the closed position of the door, and in the said position of the latch the 75 upper projection 6, which points upwardly, is overlapped at its inner side by a movable detent R, which is pivoted, as at r, horizontally to the plate K and arranged to swing in a vertical plane with the pivotal bearing of the detent R parallel with the pivotal bearing of the latch G, so as to render the said detent R capable of being swung by the said latch during 80 the movement of the latch endwise with the door in actuating the door from its open into 85 its closed position.

By the construction heretofore described it will be observed that the latch in its operative position when the door is closed is detained from above by the movable detent R 90 and from below by the stationary detent k and that the said latch rests upon the one or the other of the lugs d, according as the latch is in its operative position (shown in solid lines, Figs. 1 and 3) or in its inoperative position, 95 as shown in dotted lines in Fig. 1.

The latch-plate D is provided at each end and upon its outer side with a slight convexity or swell 8, as shown in Figs. 1, 3, and 5, and the outward swell 8 of the one or the other 100

end of the said plate engages the inner side of the latch, according as the latch is in the one or the other of its positions, and holds the latch far enough from the outer side of the said plate to avoid material interruption to the flow of water adown the said plate during rain or at any other time and to reduce the liability of the latch becoming rusted to the latch-plate to a minimum. The outer end of the latch is provided with two inclined edges 16 and 17, which slope outwardly and toward each other from the extremities of the projections 6 and 7 of the latch—that is, the said edges diverge inwardly and meet centrally of the outer extremity of the latch. It will be observed, therefore, that the upper inclined edge 16 slopes upwardly and inwardly to the upper extremity of the upper projection 6 and the lower inclined edge 17 slopes downwardly and inwardly to the lower extremity of the depending projection 7.

During the actuation of the door from an open into its closed position the lower inclined edge 17 comes, as shown in Fig. 4, into engagement with the stationary detent $\bar{z}$ and is acted upon by the said detent in the direction required to lift the latch and enable the lower projection 7 to pass over the said detent. Also during the actuation of the door from an open into its closed position the upper inclined edge 16 comes into engagement with the movable detent R, as shown in Fig. 4, and swings the said detent outwardly to permit the upper projection 6 to pass in under the said detent, and the said projection 6 has its inner side sloping downwardly and inwardly toward the axis of the latch to accommodate the swinging of the said detent R into an inoperative position, and the said detent is provided with arms 10, at which it may be conveniently taken hold of in rendering the same inoperative.

The plate K is provided also with a seal-receiving member 12, which bridges the path of the latch G at the outer side of the said path, and the said member 12 is provided with a lateral perforation 13, arranged to register with a lateral perforation 14, formed in the free end of the latch when the latch is in its operative position and held to the said plate by the detents, and the said perforations accommodate the application of a seal S. (Shown only in Fig. 3.)

What I claim is—

1. A fastener for a sliding door, comprising a latch pivoted to the latch-plate and provided, at its outer end, with two projections formed at the top and bottom respectively of the latch, which latch has also two inclined edges which are formed upon the outer end of the

latch and diverge in the direction of the inner end of the latch; a latch-plate adapted to be secured to the door and provided upon its outer side with a lug arranged to form a seat for the latch upon swinging the latch from its operative into its inoperative position; a detent-bearing plate adapted to be secured to the door-casing and provided with a detent-forming lug arranged to overlap the inner side of the lower projection of the latch in the operative position of the latch when the door is closed, and a movable detent free to swing in a vertical plane and pivoted to the last-mentioned plate, which detent has its pivotal bearing parallel with the pivotal bearing of the latch, and the said last-mentioned detent being arranged to overlap the inner side of the upper projection of the latch in the operative position of the latch.

2. A fastener for a sliding door, comprising a latch-plate adapted to be secured to the door and provided upon its outer side with two outward swells arranged at opposite ends respectively of the plate, said plate also having two seat-forming lugs arranged a suitable distance apart between the aforesaid swells and in the same or approximately same plane horizontally; a latch pivoted to the latch-plate centrally between the two seat-forming lugs, and a plate adapted to be secured to a door-casing and provided with means instrumental in retaining the latch in an operative position, and the arrangement of the parts being such that the latch has bearing on the one or the other of the aforesaid seat-forming lugs according as it is in its operative position or has been swung in its opposite and inoperative position.

3. A fastener for a sliding door, comprising a latch-plate adapted to be secured to the door and provided upon its outer side with two seat-forming lugs arranged a suitable distance apart horizontally; a latch pivoted to the latch-plate between the two seat-forming lugs, and a plate adapted to be secured to a door-casing and provided with means instrumental in retaining the latch in an operative position, and the arrangement of the parts being such that the latch has bearing on the one or the other of the aforesaid lugs according as it is in its operative position or has been swung in its opposite and inoperative position.

In testimony whereof I sign the foregoing specification, in the presence of two witnesses, this 9th day of June, 1903, at Cleveland, Ohio.

PATRICK J. CASSERLY.
